VERTICALLY ADJUSTABLE COMBINATION CABINET AND DESK

Boad S. L. Freitag, Balboa Island, Calif.

Application August 23, 1949, Serial No. 4,653

Term of patent 14 years

(Cl. D33—19)

To all whom it may concern:

Be it known that I, Boad S. L. Freitag, a citizen of the United States, residing at Balboa Island, in the county of Orange and State of California, have invented a new, original, and ornamental Design for Vertically Adjustable Combination Cabinet and Desk, of which the following is a specification, reference being had to the accompanying drawing, forming part thereof.

Figure 1 is a perspective view showing the front, top, and one side of a vertically adjustable combination cabinet and desk showing my new design. In this figure the article is closed and in lowered position.

Figure 2 is a view similar to Figure 1, but showing the article in open and elevated position.

I claim:

The ornamental design for a vertically adjustable combination cabinet and desk, as shown.

BOAD S. L. FREITAG.
